(57) **CLAIM**

The ornamental design for a chair as shown and described.

DESCRIPTION

The file of this patent application contains at least one drawing/photograph which is in grayscale. Copies of this patent with the grayscale drawing(s)/photograph(s) will be provided by the Office upon request and payment of the necessary fee.

FIG. 1 is a front, left-side perspective view of a chair showing my design;

FIG. 2 is a front perspective view of the chair of FIG. 1; FIG. 3 is a rear perspective view of the chair of FIG. 1; FIG. 4 is a left-side perspective view of the chair of FIG. 1; FIG. 5 is a right-side perspective view of the chair of FIG. 1;

FIG. 6 is a top perspective view of the chair of FIG. 1; and, FIG. 7 is a bottom perspective view of the chair of FIG. 1. The parallel lines that extend across the outer edges and surfaces of the seat, backrest, and legs of the chair represent shading or contour lines rather than claimed ornamental features.

The grayscale contrast represents a contrast in appearance only and does not represent any particular color, material, texture, or finish.
